UNITED STATES PATENT OFFICE.

FRANK E. GRUNWALDT, OF SEATTLE, WASHINGTON, ASSIGNOR TO GABRIEL TUBULAR FURNACE CO. INC., OF TACOMA, WASHINGTON, A CORPORATION OF WASHINGTON.

FURNACE.

Application filed October 2, 1926. Serial No. 139,204.

My invention relates to improvements in furnaces and is in the nature of an improvement on the furnace disclosed in United States Letters Patent No. 1,440,071, issued 5 Dec. 26, 1922.

The general objects of my invention are to improve and simplify the construction of furnaces of this nature and to render the same more reliable, efficient and economical 10 in operation.

More specific objects of the invention are, to provide an improved arrangement and spacing of the warm air tubes in the furnace: To improve the general shape and 15 construction of the furnace, making the same cheaper and easier to manufacture and more efficient in operation: To provide an improved sectional fire pot and grate construction: To provide a furnace front of 20 sheet steel rather than of cast metal construction: To provide novel air inlet means connected with the front door of the furnace and to provide novel arrangement of the water pan in the furnace front.

25 Other and more specific objects will be apparent from the following description taken in connection with the accompanying drawings.

In the drawings Figure 1, is a perspective 30 view of a furnace constructed in accordance with my invention showing parts broken away to reveal the interior.

Fig. 2, is a vertical sectional view of the same.

35 Fig. 3, is a cross section substantially on broken line 3—3 of Fig. 2.

Fig. 4, is a detached view in elevation of the all steel furnace front.

Fig. 5, is a detached perspective of parts 40 of the sectional fire pot and grate construction showing said parts separated a short distance to better illustrate their construction.

Like reference numerals designate like 45 parts throughout the several views.

The drawings show a furnace embodying a lower fire box and ash receptacle 10, a larger combustion compartment 11, above the ash receptacle 10, and the smaller heating dome 12 on the top of the combustion compartment 11. A sheet steel furnace front 13, is secured to the open front end 50 of the combustion compartment 11 and is

connected by an extension portion 14 with the lower ash receptacle 10. A smoke pipe 55 15, is connected with the lower portion of the combustion compartment 11 at the rear and another smoke pipe 16 is connected with the lower portion of the heating dome 12 at the rear. Both pipes 15 and 16 are 60 adapted to connect with the same vertical smoke pipe 17. An air inlet or draft damper 18 is provided for the pipe 17 and a pipe damper 20 of the usual form is provided in the pipe 16 and is connected with an operating rod 21 that extends to the front 65 of the furnace. This pipe damper 20 will ordinarily be closed except when the fire is being started or an unusually strong draft is desired.

The combustion compartment 11 is larger than the ash receptacle 10 and larger than the heating dome 12 thereby affording upper and lower shelf like portions 22 and 23 respectively at the top and bottom of said 70 combustion chamber that project beyond the limits of the ash receptacle and heating dome and afford room for a plurality of vertically arranged steel heat tubes 24 that extend between the upper and lower shelves 75 22 and 23 a short distance inwardly from the walls of the combustion compartment 80 and are open at both ends. These tubes 24 are spaced apart a substantial distance at the forward end to permit heated gases to 85 circulate freely therebetween and the spacing is lessened toward the rear the peripheries of the tubes directly in the rear of the furnace being substantially in contact with each other.

This is an important feature because it compels the major portion of the heated gases to pass outwardly between the tubes near the front of the combustion chamber 11 and to travel in the narrow space between the outer sides of the tubes and the 90 wall of the combustion chamber 11 to reach the smoke pipe 15. This insures that the heated gases will not pass directly out of the smoke pipe 15 but will give up the greater portion of their heat through the tubes 24 95 and through the walls of the combustion compartment 11 before they reach the smoke pipe 15.

Two of the tubes 24 near the rear of the furnace extend downwardly alongside of the 100 ash receptacle 10 as indicated at 19 and serve 105

as legs for the rear of the furnace, air openings 29 are provided in the leg portions 19. The front of the furnace is supported by the bottom edge of the steel furnace front 13.

5 The steel front 13 of the furnace is provided with an upper opening 25 for a water pan 26, a medial opening 27 for double furnace doors 28 and 30 and a lower opening 31 for an ash door 32. The edges of the 10 steel front 13 are bent as shown in Figs. 1, 3 and 4 to afford suitable flanges 33 to which an outer drum 34, that extends entirely around the furnace and provides an air circulation space, is secured. The water pan 15 26 is provided on the sides and bottom with a flange 35 that is securely clamped by bolts 36 between a frame piece 37 and the steel furnace front 13, thus affording an easily 20 constructed, easily assembled and efficient way of supporting said water pan. Packing is preferably used between the furnace front 13 and the flange 35 so as to form a seal and exclude smoke and dust and impure air. The location of the water pan 25 above the combustion compartment and directly in front of the heating dome is of advantage in making for compactness of construction and giving the proper amount of evaporation.

30 The upper coal door 28 is of substantially dish shape and has a plate 38 on its inner side affording an air space 40. Tubes 41, preferably two in number, are supported by the plate 38, communicate with the air space 35 40 and extend into the combustion chamber 11 as shown to furnish fresh air for hot blast or combustion purposes to the upper portion of the combustion chamber.

40 The furnace is substantially all of sheet steel construction and all joints are electrically welded making them absolutely tight and proof against the passage of dust or gas from the gas chamber to the clean air chambers. The ash compartment and heating dome are of the same size and are disposed in alignment relative to each other.

45 The fire pot of the furnace is of oblong shape and is formed of a plurality of grate sections adapted to fit within the upper end 50 of the lower ash compartment section of the furnace and to be supported on the lower shelf portion 23. This fire pot comprises end sections 42 and side sections 43 adapted to interfit and form the receptacle for the 55 coal. Both the end sections 42 and the side sections 43 have outwardly directed flanges at their top edge adapted to rest on the lower shelf like portion 23 of the combustion chamber.

60 The ends of the sections 43 are provided with notches 44 adapted to interfit the ends of the end sections 42 and have studs 45 on the bottom adapted to set within notches 46 in the bottoms 47 of the end sections.

65 The bottoms 47 of the end sections are

provided with slotted draft openings 48. The side sections 42 have inwardly directed bottom flanges 50 provided with grooves 51 for the reception of pivot studs 52 on the ends of grate bars 53 that extend crosswise 70 of the fire pot. The grate bars 53 have downwardly extending arms 54 that are pivotally connected with an operating link 55 which extends outwardly through a slot 59 in the front of the furnace and is pivotally 75 connected with the top end of a shaker member 56. A shaker arm or lever 57 is adapted to be removably connected with the top end of the shaker member 56. The bottom end of shaker member 56 rests on a cam 58 and has a pivot 60 on the end thereof that extends down through said cam and through a plate 61 at the bottom of the furnace front. The cam 58 has a foot piece 62 extending 80 outwardly therefrom by which it may be turned to lift the member 56 and release a notch 63 on the shaker bar 55 from engagement with the furnace front at the bottom of the slot 59, thus permitting the grate bars 53 to be oscillated in shaking down the fire. When the cam 58 is replaced in the position 85 in which the outer end of the shaker bar 55 is lowered the notch 63 will engage with its catch formed by the front of the furnace and lock the grate bars in their normal horizontal position.

90 The efficiency of this furnace is greatly increased by the additional heating surface afforded by the tubes 24 and the heating dome 12 on the top of said furnace. When the furnace is operating normally the damper 20 in the pipe 16 will usually be closed thus preventing the direct escape of heated gases from the heating dome 12. The heated 95 gases in the combustion chamber 11 must necessarily pass outwardly between and around the tubes 24 before reaching the smoke pipe 15 thus insuring a maximum heating of the air that is circulating through 100 said tubes.

105 The foregoing description and accompanying drawings clearly disclose a preferred embodiment of my invention but it will be understood that this disclosure is 110 merely illustrative and that such changes in the device may be resorted to as are within the scope and spirit of the following 115 claims.

I claim:—

120 1. In a furnace, a fire box having a smoke outlet and a plurality of heat tubes between said fire box and said smoke outlet, the tubes adjacent said smoke outlet being close together and the tubes further removed from 125 said smoke outlet being spaced apart.

125 2. In a furnace, a fire box, having a smoke outlet, and a plurality of heat tubes arranged around said fire box between said fire box and said smoke outlet, the tubes adjacent 130 said smoke outlet being close together and

the tubes further removed from said fire box being spaced successively increasing distances apart.

3. In a furnace, a combustion compartment, a smoke pipe connected therewith, a plurality of vertical tubes arranged around said combustion compartment and spaced inwardly from the wall thereof said tubes being close together adjacent the entrance to said smoke pipe to restrict the passage of heated gases therebetween and the tubes further removed from said smoke pipe being spaced further apart, and fire pot means in the bottom of said combustion compartment 15 within the space surrounded by said tubes.

4. In a furnace, a combustion compartment of oval shape having a fuel inlet opening at the front and having a smoke outlet opening at the rear, a plurality of vertical tubes arranged in continuous formation around said compartment and spaced inwardly from the wall thereof, the tubes being omitted from the space directly in front of said fuel inlet opening, the tubes extending from front to rear of said compartment being spaced apart gradually decreasing distances and the tubes directly in the rear of said compartment being substantially in contact with each other and a fire pot in 30 the bottom of said combustion compartment within the space surrounded by said tubes.

5. In a furnace, a combustion compartment and a plurality of substantially vertical heating tubes arranged around said combustion compartment adjacent the wall

thereof certain of said tubes extending downwardly below the combustion compartment to form legs for the furnace.

6. In a furnace, a combustion compartment, a smaller ash receptacle disposed therebelow and a plurality of upright heating tubes open at both ends and extending through the combustion compartment so as to leave a narrow passageway between the 40 tubes and the walls of the combustion compartment, certain of said tubes extending downwardly on the outside of the ash receptacle to form legs for supporting the furnace, said downwardly extending tubes having 45 holes therein.

7. In a sheet steel furnace, a larger combustion compartment of oval shape, a smaller heating compartment disposed on the top of said combustion compartment and communicating therewith, a smaller ash compartment disposed below said combustion compartment, a plurality of heat tubes extending through said combustion compartment outside the limits of said heating compartment 50 and said ash compartment said tubes being open at both ends, two of said tubes towards the rear of said furnace extending downwardly on the outside of said ash compartment to form legs for supporting said furnace said leg tubes having openings in their 55 sides.

The foregoing specification signed at Tacoma, Washington, this 17th day of Sept., 1926.

FRANK E. GRUNWALDT.
